ADOLPH RUBIN, OF ST. LOUIS, MISSOURI, ASSIGNOR, BY MESNE ASSIGNMENTS, TO ARCADE MANUFACTURING COMPANY, OF FREEPORT, ILLINOIS, A CORPORATION OF ILLINOIS.

SPRINGLESS FASTENER.

Application filed July 17, 1924. Serial No. 726,527.

This invention relates to springless fasteners of the kind that are used on doors of refrigerators, ice boxes and various other structures.

5 The main object of the invention is to provide an inexpensive, springless fastener of simple design, that is equipped with a means for positively moving the latch into locking engagement with the keeper during the operation of closing the door with which the fastener is used.

Figure 1 of the drawings is a front elevational view of a springless fastener constructed in accordance with my invention, 15 showing the parts of the fastener in the position they assume when the door is closed.

Figure 2 is an end elevational view of said fastener, looking sidewise at the keeper.

Figure 3 is a rear elevational view of the 20 fastener casing with the back plate of the casing broken away so as to more clearly illustrate the construction and arrangement of the latch and the plunger that moves same into operative relationship with the keeper; 25 and

Figure 4 is a horizontal sectional view, taken on the line 4-4 of Figure 1.

Referring to the drawings which illustrate the preferred form of my invention, 30 A designates the latch of my improved fastener which is preferably constructed in the form of a lever pivotally connected at 1 to a casing B and provided at one end with a handle 2 and at its opposite end with 35 a portion 3 that is adapted to co-operate with a keeper, designated as an entirety by the reference character C. The casing B is usually mounted on the door α with which the fastener is used and the keeper C is mounted 40 on a stationary part of the structure at one side of the door opening. The particular way in which the casing and keeper are mounted on the parts of the structure with which they co-operate is immaterial, and instead of arranging the co-operating parts of 45 the fastener in such a way that the latch moves over the upper end of the keeper and then downwardly behind the keeper during the operation of closing the door, as herein 50 illustrated, said parts can be so arranged that the latch moves under the lower end of the keeper and then upwardly behind the keeper, during the operation of closing the door, assuming, of course, that the door 55 swings on a vertical axis. In instances where

the fastener is used with a door that swings on a horizontal axis, the keeper can be so arranged that the latch will either move to the left behind the keeper, or move to the right behind the keeper as the door approaches its 60 fully closed position. It is preferable to construct the latch A in such a way that gravity holds the latch in an inclined position with the handle 2 of the latch A depressed and the keeper-engaging portion 3 65 of the latch raised when the door is in its open position, this being effected either by counterweighting the latch, or by arranging the pivot 1 of the latch at a point intermediate the center of the latch and the end of 70 the latch that constitutes the portion 3 which co-operates with the keeper. The keeper C may be formed in various ways, but it will usually consist of a member arranged at substantially right angles to the latch 75 A and carried by a shank 4 that projects forwardly from a supporting plate 5 which is connected by means of fastening devices to the stationary part of the structure at one side of the door opening. Said keeper is 80 provided at its rear side with an inclined surface 6 that is spaced away from the supporting plate 5 so as to form a notch or open-ended slot that receives the portion 3 of the latch A when the door is closed, and said keeper is provided at its front side with an oppositely-inclined surface 7, which, in some instances, co-operates with the portion 85 3 of the latch to move the latch in a direction to permit said portion 3 to move behind the keeper or become positioned at the rear side of same, depending upon how the casing B and keeper C are arranged on the door and stationary part of the structure. 90

When said parts are arranged in the manner herein illustrated the portion 3 of the latch A will stand in an upwardly-inclined position when the door is open, and will clear the upper end of the keeper C as the door moves towards its closed position.

As previously stated, my improved fastener is provided with means for positively moving the latch into engagement with the keeper during the operation of closing the door. Said means preferably consists of a plunger D arranged in an inclined position in the casing B, a cam E adjacent the keeper which the outer end of the plunger D engages during the operation of closing the door, thereby causing said plunger to move 100 105 110 115 116

inwardly, and a lug or other suitable part 8 on the latch A on which the inner end of said plunger D exerts pressure in a direction to cause the portion 3 of the latch to move into operative relationship with the keeper C, namely, behind the keeper. In the form of my invention herein illustrated the cam E is formed by an inclined surface on one side of the shank 4 which carries the keeper C, and the outer end of the plunger D is beveled slightly, as shown in Figure 4, so as to insure said plunger riding freely over the cam E. In order to prevent the keeper C from springing sideways under the influence of the pressure which the plunger D exerts on the cam E during the operation of moving the latch into locking engagement with the keeper, I prefer to provide the portion 3 of the latch with an angularly-disposed projection 3^a that rides over the side face of the keeper C located farthest away from the door when said portion 3 is moving into locking engagement with the keeper, said projection 3^a serving virtually as a backing or thrust-resisting element for the keeper that prevents it from springing laterally away from the edge of the door. As the latch A swings on an arc, it is preferable to impart a slight curvature to the keeper C, as shown in Figure 1, and mount said keeper on the stationary part of the structure in such a way that it will be concentric with the axis of movement of the latch A, the angularly-disposed projection 3^a on the latch A not only preventing the keeper from being subjected to strains which tend to loosen the fastening devices that are used to secure the supporting plate 5 of the keeper in position, but also facilitating the installation of the keeper and the casing B of the fastener, for if care is taken to arrange the convexed side face of the keeper C in engagement with the projection 3^a on the latch during the operation of securing the keeper supporting plate 5 in position, the two main elements of the fastener, namely, the casing B and the keeper supporting plate 5 will be spaced apart the right distance to cause the latch and keeper and the plunger D and cam E to function properly when the door is opened and closed.

When the door is open the portion 3 of the latch A will stand in an upwardly-inclined position and the plunger D will be extended, as shown in Figure 3. When the door is moved towards its closed position the portion 3 of the latch passes over the upper end of the keeper C, and at about the time said portion 3 reaches the point where it can swing downwardly behind the keeper, the beveled end of the plunger D strikes against the cam E, and in riding over the said cam is moved inwardly so as to exert

pressure on the lug 8 of the latch in a direction to positively force the portion 3 of the latch downwardly over the inclined surface 6 on the rear side of the keeper. As the portion 3 of the latch moves downwardly over the inclined rear edge 6 of the keeper, the inward pressure that is exerted on the door forces the door tightly closed, and after the door has reached its fully closed position, the portion 3 of the latch 75 is retained in engagement with the keeper C by the co-action of the cam E, plunger D and lug 8 on the latch. When it is desired to open the door, the handle 2 of the latch is pressed downwardly, thereby causing the lug 8 on the latch to move the plunger D outwardly, and as said plunger moves outwardly over the inclined face of the cam E, the portion 3 of the latch swings 80 upwardly to a point where it can pass over the upper end of the keeper C when a forward pull is exerted on the handle of the latch.

A fastener of the construction above described will securely hold a door in its 90 closed position; it is easy to manipulate, and it is of such simple design that it is inexpensive to manufacture and is not liable to get out of order when in use. In most instances the keeper C, shank 4 and supporting plate 5 will be constructed as a single unit from cast metal, and the casing B of the fastener will consist of a casting having a hollow portion that houses the plunger D, the pivot of the latch A and the lug on said latch that co-operates with the plunger D. The pivot 1 on which the latch oscillates is formed by an integral lug on the front wall of the casing B, and said latch is retained in operative position on said lug by a removable back plate B' that is held in position by a screw 1^a that enters a threaded hole in the lug that constitutes the pivot 1 of the latch. The plunger D is provided with an angularly-shaped front portion that 95 projects through a correspondingly-shaped hole in the side wall of the casing and a cylindrical-shaped inner portion D' that slides freely in a perforated lug 9 on the inner side of the front wall of the casing, as 100 shown in Figure 3, the end of said cylindrical-shaped portion D' being upset so as to limit the outward movement of the plunger D.

Having thus described my invention, what 105 I claim as new and desire to secure by Letters Patent is:

1. In a swinging door fastener, the combination of a hinged door, a latch mounted on said door in such a manner that gravity 110 tends to hold said latch in an inactive position with relation to the keeper when the door is open, an actuating member for said latch mounted on the door, and a stationary 115 part associated with the keeper and ar- 120

- ranged so that the movement of the door towards its closed position causes said stationary part to impart movement to said actuating member and cause said member to 5 positively move the latch into locking engagement with the keeper.
2. A door fastener, comprising a latch, a keeper, a cam arranged adjacent the keeper, and a plunger carried by the part on which 10 the latch is mounted and arranged to engage said cam and be moved by same in a direction to positively move the latch into operative relationship with the keeper during the operation of closing the door.
- 15 3. A door fastener, comprising a keeper, a pivotally-mounted latch, a casing which carries said latch, a plunger in said casing, a part on the latch adapted to be engaged by said plunger and moved by same in a direction to cause the latch to engage the keeper, and means for causing said plunger to actuate the latch during the operation of closing the door.
- 20 4. A door fastener, comprising a stationary keeper provided with a cam, a movable casing provided with a pivotally-mounted latch, an element on said casing that is adapted to be actuated by said cam to move the latch into locking engagement with the 25 keeper during the operation of closing the door, and a device on the latch that is adapted to engage the keeper and prevent it from springing sidewise due to the pressure produced by the engagement of said element with said cam.
- 25 5. A door fastener, comprising a casing adapted to be connected to a door and provided with a pivotally-mounted latch, a supporting plate adapted to be connected to a stationary part of the structure and provided with a keeper, and a cam arranged 30 at one side of said keeper, a laterally-projecting part on said latch, and a plunger in said casing that acts on said part and which is so arranged that it will engage said cam 45 and be moved by same in a direction to cause the latch to pass behind the keeper during the operation of closing the door.
- 35 6. A door fastener, comprising a casing adapted to be connected to a door, a pivotally-mounted latch on said casing, a stationary keeper arranged so that said latch can pass behind the same and provided with a convexed surface, a projection on the latch that is adapted to ride over said convexed 50 surface, a cam arranged adjacent the keeper, and a plunger in the casing that is adapted 55 to be moved inwardly by said cam during the operation of closing the door so as to exert pressure on the latch in a direction to 60 move it behind the keeper.
7. A door fastener, comprising a casing adapted to be connected to a door, an unbalanced, pivotally-mounted latch on said casing, a supporting plate adapted to be secured to a stationary part of the structure adjacent the edge of the door, a shank projecting forwardly from said plate, a keeper on said shank, an inclined surface on one side of said shank that acts as a cam, an 65 angularly-disposed lug on said latch, and a reciprocating plunger in the casing arranged to act on said lug and disposed so that it is moved by said cam in a direction to cause 70 the latch to engage the keeper during the 75 operation of closing the door.
8. A door fastener, comprising a casing adapted to be connected to a door, a pivotally-mounted, unbalanced latch on said casing provided with an angularly-disposed 80 lug, a reciprocating plunger on said casing arranged so that the inner end of same will act on said lug, and a stationary keeper and cam arranged so that the cam will act on 85 the plunger and cause it to move the latch into operative relationship with the keeper during the operation of closing the door.

ADOLPH RUBIN.
